AUTOMOBILE GRILLE

Eugene Bordinat, Jr., Bloomfield Hills, Mich., assignor to Ford Motor Company, Dearborn, Mich., a corporation of Delaware

Filed Nov. 13, 1961, Ser. No. 67,504

Term of patent 7 years

(Cl. D14—18)

FIG. 1 is a perspective view of an automobile grille, showing my new design. It will be understood that the fragmentarily shown grille pattern is continuous as shown in FIG. 2;

FIG. 2 is a front elevational view of the automobile grille;

FIG. 3 is a top plan view;

FIG. 4 is an enlarged side elevational view; and

FIGS. 5, 6, 7, 8 and 9 are enlarged sectional views taken substantially through lines 5-5, 6-6, 7-7, 8-8 and 9-9, respectively, of FIG. 2.

I claim:

The ornamental design for an automobile grille, substantially as shown.
